4 Claims. (Cl. 235—79.5)

This invention relates to calculating machines.

More particularly this invention relates to calculating machines of the slide-rule type.

The invention will be described as developed for use in determining roll speeds for multipass rolling mills although it will be appreciated that the invention is not limited to such application.

As is well known, when carrying out multistage reduction upon a tubular ingot which has been heated to the roll temperature by sending the ingot through several successive roll stands, and without using a broach, the diameter and wall thickness of the ingot are reduced in stages and to this end the rollers at each stand are given an appropriate pass form and speed.

Using modern drive systems, it is possible so to alter the speeds of the rollers at the individual stands, that the desired end-product is in a required condition and predetermined tolerances maintained.

When supplying a rolling mill installation of this sort, it has hitherto been necessary for the supplier to provide the operator with instructions for determining the necessary sequence of roller speeds, these instructions usually being in the form of data sheets in which appropriate calculation factors are presented in tabular and graph form.

The fact that the operator has to be given such instructions and information regarding the various factors involved in setting the roller speeds, demonstrates how complex are the theoretical considerations and mathematical knowledge required in order to ensure proper adjustment of the installation both prior to and during production.

In order to considerably simplify the task of the operator, it is desirable for the supplier to provide an aid by means of which the operator, in accordance with a predetermined scheme and without the need for knowledge of the fundamental principles involved, could determine roller speeds at each particular stand and thus ensure the desired deformation, it being also desirable that the operator should be able to determine these values for different types of installation.

One method of solving this problem is for the supplier to provide slide rule devices of known type, the required values being calculated by appropriate manipulation for slides and cursors. However, it must be borne in mind that it is necessary for the supplier either to provide varying numbers of interchangeable slides (for example if it is required to deal with what are known as combined multipass rolling mill installations), or to avoid this, by providing several scales on one slide.

However, all these approaches suffer the disadvantage that the devices concerned either involve interchangeable parts, which may lead to confusion, or, in the event that several scales are carried on one slide, detract from the straightforwardness of operation and thus demand a great deal of attention and accuracy on the part of the operator.

One object of the present invention is to provide a calculating machine in which the above discussed disadvantages are overcome at least in part.

According to the present invention, a calculating machine, of the slide-rule type, includes a frame member, a

2

longitudinally extending body member mounted on said frame member so as to be rotatable relative thereto about a longitudinal axis of said body member, a number of slide members arranged in longitudinally extending grooves about the outer periphery of said body member, said slide members being adapted to slide in the longitudinal direction in said grooves, scale markings on said slide members and scale markings on said body member, and a number of cursors slidably mounted on said body member so as to be able to slide in the longitudinal direction along said body member, each of said cursors being adapted to provide co-operation between certain of said scale markings on said slide members and certain of said scale markings on said body member.

One embodiment of a calculating machine in accordance with the present invention will now be described by way of example with reference to the accompanying drawings, in which:

FIGURE 1 is a part-sectional side elevation of the machine, and

FIGURE 2 is a cross-sectional elevation taken perpendicularly to the longitudinal axis of the machine.

Referring now to the drawings, the machine includes a body member 1 which is rotatably mounted on spindles 2 and 3 which are mounted in a frame member 4. The spindle 2 is fixed in the frame 4 and the body 1 rotates on its stub. One end of the spindle 3 is fixed in the body 1 and the other end is rotatable in a hole in the frame 4, there being provided a pinch-nut assembly 5 whereby the body 1 may be locked in any rotational position.

Provided on the spindle 2 is a hollow arm 6 which is rotatable on the spindle 2 relative to the frame 4, this arm 6 being locked in any desired position by means of a further pinch-nut assembly 7. The arm 6 carries a lamp housing and reflector 8 whereby the body 1 may be illuminated.

Arranged in slots about the periphery of the body 1 are slides 9, these slides 9 carrying markings which co-operate with further markings on the body 1. Each of the slides 9 is bridged by one of a number of cursors 10 and 13, whereby each slide 9 and its associated markings may be used in the manner of a conventional straight slide rule.

Arranged within the body 1, mounted so as to be rotatable about its axis 16 is a cylinder 11 which carries, arranged in slots about its periphery, six slides 12, each of which carries markings relevant to a particular set of calculations.

Provided in the body 1 is a slot through which one slide 12 at a time on the cylinder 11 may be seen. The cursor 13 is curved so as to cover two sides of the body 1, including the slot through which the slides 12 may be seen and a particular one of the slides 9 such that calculations involving the markings on any one of the slides 12 and the particular one of the slides 9 may be carried out.

The cylinder 11 is locked in any desired rotational position by means of a spring-loaded hexagonal stop-pin 14 which co-operates with a hexagonal hole in the end wall of the body 1. This stop-pin 14 may be released by pressing in a wheel 15, the cylinder 11 then being rotated by rotation of the wheel 15'.

Although in the embodiment described four slides 9 and six slides 12 are provided it will be appreciated that any number may be provided in dependence upon the number of types of calculations the machine is required to carry out.

It will be further appreciated that although in the embodiment described the body 1 is basically rectangular in cross-section but having one rounded corner, it may be constructed having any convenient cross-section shape, and that the markings carried by the body 1 may be car-

ried by interchangeable members fixed to the body 1 as required.

What we claim as our invention and desire to secure by Letters Patent of the United States is:

1. A calculating machine, of the slide-rule type, including a frame member, a longitudinally extending body member mounted on said frame member so as to be rotatable relative thereto about a longitudinal axis of said body member, a number of slide members connected near the outer periphery to said body member and longitudinally slidably relative thereto, scale markings on said slide members and scale markings on said body member, and a number of cursors slidably mounted on said body member so as to be able to slide in the longitudinal direction along said body member, each of said cursors being adapted to provide co-operation between certain of said scale markings on said slide members and certain of said scale markings on said body member, a cylindrical member arranged within said body member and adapted to be rotatable about its longitudinal axis relative to said body member, a number of further slide members slidably connected near the outer periphery to said cylindrical member, each of said further slide members being provided with scale markings, said body member being formed with a longitudinally extending slot therein such that by rotation of said cylindrical member said further slide members may be viewed individually through said slot, and locking means whereby said cylindrical member may be locked in any rotational position at which one of said further slide members may be so viewed.

2. A calculating machine, of the slide-rule type, including a frame member, a longitudinally extending body member mounted on said frame member so as to be rotatable relative thereto about a longitudinal axis of said body member, a number of slide members arranged in longitudinally extending grooves about the outer periphery of said body member, said slide members being adapted to slide in the longitudinal direction in said grooves, scale markings on said slide members and scale markings on said body member, and a number of cursors slidably mounted on said body member so as to be able to slide in the longitudinal direction along said body member, each of said cursors being adapted to provide co-operation between certain of said scale markings on said slide members and certain of said scale

5 markings on said body member, including a cylindrical member arranged within said body member and adapted to be rotatable about its longitudinal axis relative to said body member, a number of further slide members arranged in longitudinally extending grooves about the outer periphery of said cylindrical member, each of said further slide members being provided with scale markings, said body member being formed with a longitudinally extending slot therein such that by rotation of said cylindrical member said further slide members may be viewed individually through said slot, and locking means whereby said cylindrical member may be locked in any rotational position at which one of said further slide members may be so viewed.

10 15 20 25 30 35 40 45

3. A calculating machine as claimed in claim 2, wherein one of said cursors is adapted to provide co-operation between the scale markings on one of said slide members on said body member and the scale markings on the particular one of said further slide members visible at any instant.

4. A calculating machine as claimed in claim 2, wherein in said locking means comprises a polygonal-in-section spring-loaded pin which in the locking position is held in co-operation with said body member, the number of side faces on said pin being equal to the number of further slide members on said cylindrical body.
